Patented July 8, 1924.

1,500,273

UNITED STATES PATENT OFFICE.

HERMAN J. SATTLER, SR., OF QUAKERTOWN, PENNSYLVANIA.

LET-OFF.

Application filed September 22, 1923. Serial No. 664,259.

To all whom it may concern:

Be it known that HERMAN J. SATTLER, Sr., a citizen of the United States, residing at Quakertown, in the county of Bucks and State of Pennsylvania, has invented certain new and useful Improvements in Let-Offs, of which the following is a specification, reference being had therein to the accompanying drawing.

10 This invention relates broadly to that class of invention known as textile and fabric weaving machines, but has more specific reference to an improved let-off, which is especially, but not necessarily, 15 adapted for use in connection with loom warp-heads.

In producing the present invention, it has been my principal aim to generally improve upon and to provide a much more simplified 20 structure than is embodied in my prior patented let-offs described and claimed in Patents Numbers 1,019,993, granted to me on March 13, 1912, and 1,418,025, granted to me on May 30, 1922.

25 Generically speaking, the patented devices referred to comprise a retarding element, preferably a weight, which serves to intermittently and periodically apply a retarding effect or load to a rotary warp-head, on 30 the end of the beam, through the medium of a band or its equivalent which slidably surrounds and is relatively movable on the periphery of the head. In order to obtain this alternate retarding action, novel means 35 is provided for temporarily securing the band to the warp-head at intervals so as to rotate therewith, this means being automatically controlled by the rotation of the head itself and being self-released at a pre-determined time, so that the aforesaid retarding element may additionally function 40 to return the band to its normal position.

More specifically speaking, the so called 45 securing or "locking" means in these prior devices positively secures the band to the warp-head by a pivoted release pin receivable in sockets in the head in one embodiment, and in another embodiment, a portion of the band is pressed or forced into 50 frictional engagement with the head. In both of the patented embodiments a "single-locking point" is obtained.

In the present embodiment, which is a decided improvement, and is much more 55 practical for certain works, the broad arrangement of parts before outlined is em-

ployed, but the band is automatically contractible and expansible; that is, it alternately decreases and increases in diameter and frictionally grips the warp-head substantially throughout its diameter and the "single-point" engagement or pressed contact is eliminated. Hence, a comparatively small band can be used to great advantage and an extremely simple structure will 60 serve; thus decidedly reducing the cost of manufacture, yet providing a highly practical device. Also, easy application and removal of the new device is assured.

Other features and advantages of the invention will become apparent during the course of the following description.

In the accompanying drawings forming a part of this specification and in which like numerals are employed to designate like 70 parts throughout the same:

Figure 1 is an end elevation of a warp-head, with a portion in section, showing one embodiment of the let-off associated therewith.

Fig. 2 is a side or edge elevation thereof.

Fig. 3 is an enlarged perspective view of cooperating details of the contracting means.

Fig. 4 is a view like Figure 1 showing a 85 different embodiment of the invention.

Fig. 5 is a fragmentary side elevation thereof.

In this application, I have illustrated two 90 different embodiments of the invention, and I wish to direct attention first to Figs. 1 to 3 wherein the letters W—H represent a conventional rotary warp-head which is secured in any appropriate manner to a cylindrical beam B. These details form no part of 95 the invention.

As before indicated, the invention resides in the provision of a band or its equivalent 1, which in this instance is circular and surrounds and seats in the grooved periphery of the head. The band has its ends 2 spaced apart to permit circumferential contraction of the same to obtain the desired uniform frictional grip. A lug 3 is fastened to the right-hand end and this lug carries spaced 100 ears 4 between which a pendulous device, in the form of a lever 5, is pivoted. In this connection, it is to be noted that the upper end of the lever is rounded as seen at 6 to provide a cam and is spaced downwardly 105 from the body portion of the lug to accommodate a chain or other flexible element 7

110

which passes over the cam. In this embodiment the upper end of the chain carries a cross-pin 8 which has detachable connection with another lug 9 secured to the opposed 5 end of the band. This connection could be of some other construction, but preferably comprises a hook-bolt 10 which is fastened to the lower end of the chain. The threaded end of the bolt extends slidably down 10 through an eye or the like 11 on one edge of the lever. A thumb nut 14 is threaded on the screw-threaded portion of the bolt and bears against the underside of the eye 11. With this construction it is obvious 15 that the chain can be adjusted for varying the degree of frictional engagement of the band 1 with said head.

A retarding element, preferably in the form of a weight 15, acts on and is secured 20 to the band by a chain, belt, or its equivalent 16. Also, a counter-weight or its equivalent 17 is carried by the lever 5. These weights will vary in size to accommodate different circumstances which are encountered. 25

For the purpose of enabling a clear understanding of the invention to be obtained, I have placed what represent imaginary lines 18, 19 and 20 on the drawing. The 30 line 18 is perpendicular and extends vertically through the axis of the head W—H as shown, while the line 19 is directed toward the right and is disposed at an acute angle to the line 18 to approximately indicate the 35 "normal position" of lever 5. The remaining line 20 is directed toward the left and indicates the approximate "releasing point" of the lever. The aforesaid head rotates in the direction of the arrow A.

40 The operation is as follows: Assuming that the parts are in the position shown in Fig. 1 it will be seen that the weight 17 on the lower end of the lever will tend to swing the lever toward the line 18, and in so doing will exert an endwise pull on the chain 7, thus drawing the ends 2 of the band together and causing the latter to firmly grip the head. Now, as the head rotates, the 45 friction grip thus obtained will "lock" the band and the weight 15 will elevate, thus momentarily retarding the rotation of the head and placing the thread under tension. At the same time, the lever 5 and its weight 17 will move successively into substantial 50 parallelism with lines 18 and 20. When it reaches the last named line, the lever will swing retrogradely and the chain 7 will slacken, thus loosening the friction grip sufficiently to permit the weight 15 to bodily 55 shift the device so that the parts assume their normal positions. Consequently, the desired let-off action is produced as in the aforesaid patented devices.

60 It is obvious that by properly adjusting 65 the band 1 by manipulating the nut 14, the

tension of the band can be regulated at will. It is also apparent that the contraction of the band is produced by the cam action of the lever on the chain passing over the upper end of the lever. 70

Referring now to Figs. 4 and 5 it will be observed that substantially the same construction is employed but the adjusting means is simply reversed. In these figures, 75 the warp-head C is likewise conventional and a suitable belt or band 21 surrounds it as shown. The spaced ends of the belt are provided with lugs 22 and 23 and the lever 24 is pivoted to the lug 22 and has its curved cam-end 24^a spaced therefrom to accommodate the chain 25 which in this instance is permanently fastened to the lever 23 and passes slidably over said rounded end. The upper free end of the chain carries the hook-bolt 26 which passed through spaced depending furcations on the lug 23. The adjusting nut 28 acts against a comparatively small cross-pin 29 on the hook which bears against and extends cross-wise of said furcations. The weight (not shown) is fastened 85 to the belt through the medium of a belt, chain, or the like 30.

The operation of this form of the device is however the same as described before.

The several features and advantages of 90 the invention have been made clear and it is evident that I have evolved and produced a very practical and advantageous device. For instance, this new structure will allow a much larger range and a variety in size 100 and it will permit use of a small round belt with a small weight of one-half pound or less on a very small edge-warp and will operate quite as efficiently as when a flat belt of several inches wide and a very heavy 105 weight is employed.

Although specific embodiments of the invention have been described and shown, it is to be understood that various minor changes in size, shape and arrangement of 110 parts may be resorted to so long as no departure from the subjoined claims is made.

I claim:

1. The combination with a warp-head; of a friction band surrounding the periphery 115 of said head and having its ends spaced apart, and means controlled by the rotation of said head for causing said ends to approach one another at predetermined intervals, whereby to radially tighten said 120 band around the head to obtain a frictional grip from end to end of the band.

2. In a let-off, a radially expandable and contractible friction grip device adapted to be mounted on a warp-head, and means controlled by the rotation of the latter for periodically and automatically expanding and contracting said device. 125

3. The structure specified in claim 2, together with a retarding element associated 130

with said device, said element also serving to circumferentially shift and return said device to its normal position at predetermined intervals.

- 5 4. A let-off comprising a transversely split friction band adapted to surround a warp-head, the ends of said band being spaced apart, a retarding element connected to said band, said element serving also to move said band circumferentially relative to the head, and means controlled by the rotation of the latter for moving the band-ends toward each other, whereby to cause the band to contract and frictionally grip the head throughout its circumference and to apply the retarding action of the weight.
- 10 5. A let-off for warp-heads comprising a retarding weight, means controlled by the rotation of the warp-head for applying the effect of the weight to the latter, and a radially expandable and contractible friction grip device for mounting said weight and means on said head.
- 15 6. A let-off for warp-heads comprising a transversely split band to encircle said head, and automatically operable expanding and contracting means associated with the opposed ends of said band.

- 20 7. The structure set forth in claim 6, said means comprising a pivoted lever and a connection between the lever and band.

- 25 8. A let-off for loom warp-heads comprising a band adapted to surround the periphery of said head, said band being transversely split and the ends thereof being spaced apart, a lever pivoted to one of said ends, and a flexible and adjustable connection between said lever and said other end, said connection being alternately rendered taut and slack by the swing of said lever.

- 30 9. A let-off for loom warp-heads comprising a band to surround said head, said band being transversely split and the opposed ends thereof being spaced apart, a

counterbalanced lever pivoted to one end of the band, and a connection between said lever and the remaining end of said band, said connection passing over the upper end of the lever so that it will be alternately rendered taut and slack by the swing of the lever.

35 10. A let-off for loom warp-heads comprising a band to surround said head, said band being transversely split and the opposed ends thereof being spaced apart, a counterbalanced lever pivoted to one end of the band, said pivoted end of the lever being rounded and spaced from the band, and a connection between said lever and the remaining end of said band, said connection passing over the upper rounded end of the lever so that it will be alternately rendered taut and slack by the swing of the lever.

40 11. A let-off comprising a circular transversely split band, lugs secured to the ends of said band; a depending lever pivoted at its upper end to one of said lugs, said pivoted end being rounded and spaced downwardly from the lug, a longitudinally adjustable flexible element having connection with the other lug, said element passing over said rounded end of the lever and being connected at its opposite end to the intermediate portion of the lever, and a weight connected with said band for moving it circumferentially relative to the part which it surrounds.

45 12. A let-off comprising a transversely split band to surround a warp-head, the ends of said band being spaced apart, a pivoted depending lever carried by one end of the band, a lug secured to the other end of the band, and adjustable connecting means associated with said lug and the first named end of the band.

In testimony whereof I hereunto affix my signature.

HERMAN J. SATTLER, Sr.
